UNITED STATES PATENT OFFICE.

JOHN E. COCKRAN, OF SAN DIEGO, CALIFORNIA.

AIR-COOLING DEVICE.

1,164,471.

Specification of Letters Patent. Patented Dec. 14, 1915.

Application filed October 1, 1914. Serial No. 864,392.

To all whom it may concern:

Be it known that I, JOHN E. COCKRAN, a citizen of the United States, residing at San Diego, in the county of San Diego and State 5 of California, have invented certain new and useful Improvements in Air-Cooling Devices, of which the following is a specification.

My invention relates to air cooling devices and has for its object the provision of a device adapted for attachment to an ordinary electric fan and so arranged that the blast of air from said fan will cause movement of a carrier which will present within 10 the path of said air successive layers of water by which the air is cooled.

Further objects and advantages of the invention will be set forth in the detailed description which now follows:—

20 In the accompanying drawing: Figure 1 is a side view of the device showing it mounted upon a fan. Fig. 2 is a detail view of the water retaining casing, and Fig. 3 is a detail view of the rotative carrier, herein- 25 after described.

Like numerals designate corresponding parts in all of the figures of the drawing.

Referring to the drawing the numeral 5 designates an ordinary electric fan comprising 30 the usual skeleton guard frame 6 and fan blades 7. The invention resides in an attachment for such fan comprising a ring or band 8 of sheet metal such as tin having its sides partially closed by plates 9 which 35 together with the band constitute a water receiving compartment 10.

A bearing post 11 is carried by one of the plates and serves as a mounting for a rotative carrier 12 comprising a hub 12^a, a peripheral band 13 and foraminous radial vanes 14 extending therebetween preferably formed of wire gauze and set at such an angle that the blast of air from the fan will cause the carrier to rotate. Therefore as the 40 blades 14 are successively passed through the water contained in the compartment 10 they elevate a limited amount of water in the form of a film into the path of the blast 45

of air from the fan. The air in passing through this film of water is markedly 50 cooled.

It is a well known fact that it is not desirable to permit the blast of a fan to blow directly upon a person and many devices have been invented for deflecting the blast 55 from a direct path. The herein-described device will efficiently serve such purpose and will at the same time utilize the power exerted by the blast when its direction of movement is changed to elevate the film of 60 water as hereinbefore set forth.

To hold the attachment in place a piece of wire is provided the bight portion of which is passed through holes 15 formed in band 13 and the terminal ends of which are 65 bent to hook formation at 16 and engaged with the rear edge of the skeleton guard frame 6.

While the elements shown and described are well adapted to serve the purposes for 70 which they are intended it is to be understood that the invention is not limited to the precise construction set forth but includes within its purview such changes as may be made within the scope of the appended 75 claim.

Having described my invention what I claim is:—

The combination with an electric fan and its usual skeleton guard of a water receptacle 80 comprising a band and plates partially closing the sides thereof, hooks carried by said band and engaged with said guard to secure the receptacle to the front of the fan, a bearing post carried by the receptacle and 85 a rotative carrier journaled upon the bearing post and comprising an annular rim and a plurality of vanes set at an angle to the line of blast from the fan, said vanes being formed of wire gauze. 90

In testimony whereof I affix my signature in presence of two witnesses.

JOHN E. COCKRAN.
